UNITED STATES PATENT OFFICE.

CHARLES W. JENKINS, OF ELLERSON, VIRGINIA, ASSIGNOR OF ONE-HALF TO LEE B. HANCOCK, OF RICHMOND, VIRGINIA.

AUXILIARY AIR-SUPPLY DEVICE.

1,294,340.

Specification of Letters Patent. Patented Feb. 11, 1919.

Application filed June 22, 1918. Serial No. 241,387.

To all whom it may concern:

Be it known that I, CHARLES W. JENKINS, a citizen of the United States, residing at Ellerson, in the county of Hanover, and 5 State of Virginia, have invented certain new and useful Improvements in Auxiliary Air-Supply Devices, of which the following is a specification, reference being had to the accompanying drawings.

10 This invention relates to an improved auxiliary air supply device for gasoline engines, and has for its primary object to provide means mounted upon the dash board of the vehicle which may be readily controlled by the operator to supply atmospheric air to the gas supply pipe or manifold to reduce the richness of the gaseous mixture.

15 It is another important object of the invention to provide a device for the above purpose which is of such construction as to minimize the possibility of foreign matter being drawn into the engine cylinders, and which may also be employed for supplying 20 water to the cylinders when they become overheated.

25 And it is a further general object of the invention to provide an accessory for motor vehicles as above characterized which consists of relatively few parts of simple form, and which may, therefore, be manufactured at comparatively small cost.

With the above and other objects in view, the invention consists in the improved construction, combination and relative arrangement of the various parts as will be herein-after more fully described, subsequently claimed and illustrated in the accompanying drawing in which similar reference characters 30 designate corresponding parts throughout the several views, and wherein:—

35 Figure 1 is a vertical sectional view illustrating the preferred embodiment of the invention;

40 Fig. 2 is a top plan view, a portion of the cap or cover being broken away;

Fig. 3 is a bottom plan view of the valve plate; and

45 Fig. 4 is a detail perspective view of the atomizing means.

50 Referring in detail to the drawing, 5

designates the body of the device, which may be of aluminum, brass or other desired metal, and is formed with a tapering cylindrical enlargement or cup 6, which affords 55 a chamber 7. The body of the device is further provided with a bore 8 which communicates with the base of the chamber 7 at one side thereof. The body wall of said chamber is preferably internally formed 60 with an annular shoulder or flange 9 to provide a seat for the perforated metal plate or disk 10, whereby said plate is spaced from the base wall of the chamber. The passage or bore 8 extends horizontally, 65 and is in communication with the lower reduced end of a vertical bore 11 formed in the body of the device. The upper end of this latter bore is permanently closed by the plug 12 having a reduced stem 13 extending 70 downwardly and preferably tapered or pointed at its terminal, which terminates adjacent to the upper end of the reduced portion of said bore.

A laterally projecting hollow stem 14 is 75 integrally formed with the body 5 and communicates with the bore 11 adjacent its upper end. This stem is exteriorly threaded for the connection of one end of a pipe 15 thereto. The other end of this pipe is 80 tapped into one side of the engine manifold or connected to the gas supply conduit between the manifold and the butterfly valve.

Within the chamber 7 a wick or other suitable porous material indicated at 16, is 85 disposed and rests upon the perforated plate 10. The wall of the chamber 7 is exteriorly provided at its upper end with a flange 17, which is notched or recessed at diametrically opposite points, as shown at 18. This 90 flange gradually increases in width from one of said recesses to the other, so that the lower edge thereof is obliquely inclined toward the wider portions of the flange. 19 designates the cap or cover for the chamber 95 7. The marginal wall of this cover is provided at diametrically opposite points on the edge thereof with the inwardly projecting lugs 20 which are adapted for engagement through the notches or recesses 18 100 and with the inclined lower edges of the flanges 17 when the cap is turned in one

direction whereby the cap will be securely held or retained in its applied position.

The cover 19 is counterbored to provide an annular groove 21 at the juncture of its top wall with the annular body wall thereof. This groove receives the edge of a leather washer disk 22 which is adapted to frictionally seat upon the upper edge of the chamber wall and effectually prevent the entrance of air or foreign matter through the notches or recesses 18 into said chamber. The top wall of the cover is provided in spaced relation to its center with an opening 23 which coincides with a similar opening 24 in the washer disk 22. A pin or stud 25 is also fixed in the top of the cover and upon the cover top a valve plate 26 is arranged. This plate is mounted for turning movement upon a pin 27 suitably fixed in the top of the cover and the washer disk. An arcuate groove or channel 28 is formed in the under side of the valve plate to receive the lug 25 which limits the rotation of said plate. The valve plate is further provided with an opening 29 which is adapted to register with the opening 23 in the top of the cover so as to admit atmospheric air through said opening into the chamber 7. The valve plate is provided upon its perimeter with a suitable finger piece 30 whereby it may be conveniently turned or rotated to open or close communication between said chamber and the atmosphere.

The device as above described may be mounted upon the instrument board of a motor vehicle by any suitable means, such, for instance, as that shown and described in my prior application for patent, filed July 28, 1917, Serial No. 183,317. It is, however, to be understood that any other desired means may be employed for this purpose, and that the device may be mounted or arranged upon any convenient part of the vehicle body.

From the foregoing description, taken in connection with the accompanying drawing, the construction and manner of operation of the device will be fully understood. Thus, for instance, when the engine is operated at a high speed, the valve plate 26 may be rotated to dispose the opening therein in registration with the opening 23 so that, in the suction stroke of the engine pistons, a partial vacuum will be created in the chamber 7 and atmospheric air drawn into said chamber. This air passes through the porous material 18 within the chamber so that it is relieved of all foreign matter, and thence through the bores 8 and 11 to the stem 14 and into the conducting pipe 15 which delivers the air into the gas supply conduit or manifold. In passing through the passage or bore 11, the air is broken up or atomized by impact against the point of

the stem 13 of the plug 12 which projects below the entrance to the stem 14. Thus by admitting atmospheric air in suitable proportion to the manifold a mixture is supplied to the engine cylinders which results in the development of maximum power with a minimum consumption of fuel. On upgrades when a rich mixture is desired, the valve plate 26 is moved to its closed position to cut off the additional air supply. The device may also be advantageously used as a primer when difficulty is experienced in starting the engine. In such cases, the operator may pour a small quantity of gasolene through the opening 29 of the valve plate into the chamber 7. This gasolene is drawn through the porous material 18 and in its passage through the perforated plate 10 and past the stem 13, is atomized. Thus, proper combustion will be facilitated so that the engine may be quickly started. Also, when the engine cylinders become overheated and preignition of the charge occurs, the cylinders may be cooled by supplying water to the chamber 7 through the opening of the valve plate, said valve plate remaining open so that water vapor and air may be drawn into the cylinders. It will thus be appreciated that I have produced a device which is of great utility and convenience in practical use and at the same time is quite simple in its construction, as well as positive and reliable in operation. The device possesses but few parts which are very compactly arranged so that it will occupy but little space upon the instrument board or dash of the vehicle. As these parts likewise are of relatively simple form, it will be appreciated that the invention may be produced at small manufacturing cost.

While I have herein shown and described the preferred construction and arrangement of the several elements, it is to be understood that the device is susceptible of many modifications therein and I, therefore, reserve the privilege of resorting to all such legitimate changes as may be fairly embodied within the spirit and scope of the invention as claimed.

I claim:—

A device of the character described including a body member having an air receiving chamber and an outlet communicating with one end of said chamber, a removable closure for the other end of the chamber provided with an annular marginal flange having an internal annular groove, a packing washer engaged at its perimeter in said groove and adapted to seat upon the end of the chamber wall, the closure body and said washer having coinciding air inlet openings, a rotary valve plate engaged upon the opposite side of the closure, com-

mon means for permanently fastening the washer and the valve plate to the closure, said plate being also provided with an opening therein adapted to register with the 5 opening in the closure upon the rotation of said plate in one direction, and stop means for limiting the rotation of said valve plate.

In testimony whereof I hereunto affix my signature in the presence of two witnesses.

CHARLES W. JENKINS.
